US00D921132S

(12) **United States Design Patent** (10) **Patent No.:** **US D921,132 S**
(45) **Date of Patent:** **** Jun. 1, 2021**

(54) **EXERCISE MACHINE**

(71) Applicant: **TONAL SYSTEMS, INC.**, San Francisco, CA (US)

(72) Inventors: **Aly Orady**, San Francisco, CA (US); **Dan Harden**, Palo Alto, CA (US)

(73) Assignee: **TONAL SYSTEMS, INC.**, San Francisco, CA (US)

(**) Term: **15 Years**

(21) Appl. No.: **29/681,193**

(22) Filed: **Feb. 22, 2019**

Related U.S. Application Data

(63) Continuation-in-part of application No. 29/665,574, filed on Oct. 4, 2018.

(57) **CLAIM**

The ornamental design for an exercise machine, as shown and described.

DESCRIPTION

FIG. 1 is a front perspective view of a first position of an exercise machine, according to an embodiment of our new design;

FIG. 2 is a front side view thereof;

FIG. 3 is a rear side view thereof;

FIG. 4 is a left side view thereof;

FIG. 5 is a right side view thereof;

FIG. 6 is a top plan view thereof;

FIG. 7 is a bottom plan view thereof;

FIG. 8 is a front perspective view of a second position of an exercise machine, according to an embodiment of our new design;

FIG. 9 is a front side view thereof;

FIG. 10 is a rear side view thereof;

FIG. 11 is a left side view thereof;

FIG. 12 is a right side view thereof;

FIG. 13 is a top plan view thereof; and,

FIG. 14 is a bottom plan view thereof.

The broken lines shown in the figures are for purposes of illustrating portions of the exercise machine, which form no part of the claimed design.

1 Claim, 14 Drawing Sheets
